UNITED STATES PATENT OFFICE.

JOHN THOMAS TULLIS, OF HOPE, ARKANSAS, ASSIGNOR OF ONE-HALF TO ROBERT MUNDAY, OF FULTON, ARKANSAS.

CLOTH MEASURING AND FOLDING MACHINE.

1,238,961.

Specification of Letters Patent. Patented Sept. 4, 1917.

Application filed March 14, 1916, Serial No. 84,143. Renewed July 13, 1917. Serial No. 160,482.

To all whom it may concern:

Be it known that I, JOHN T. TULLIS, a citizen of the United States, residing at Hope, in the county of Hempstead and State of Arkansas, have invented a new and useful Cloth Measuring and Folding Machine, of which the following is a specification.

The present invention is a machine adapted to hold a bolt of cloth, and having means whereby the cloth can be measured as it is unrolled from the bolt, and it is the object of the invention to provide a novel and improved appliance of that character adapted for use in drygoods stores and elsewhere, for conveniently measuring, cutting and folding the cloth, eliminating the trouble, time and waste incident to the ordinary method of measuring, cutting and folding cloth taken from bolts.

The present machine has novel means for receiving the bolt of cloth, means for measuring the cloth as it is unwound, novel means for folding the measured cloth, and novel means for severing or cutting the cloth, the folded cloth being readily removed from the machine in order that it can be wrapped.

With the foregoing and other objects in view which will appear as the description proceeds, the invention resides in the combination and arrangement of parts and in the details of construction hereinafter described and claimed, it being understood that changes in the precise embodiment of the invention herein disclosed can be made within the scope of what is claimed without departing from the spirit of the invention.

40 The invention is illustrated in the accompanying drawings, wherein:

Figure 1 is a plan view of the machine, portions being broken away.

Fig. 2 is a side elevation thereof, portions being broken away.

Fig. 3 is a fragmental, opposite side elevation.

Fig. 4 is a view illustrating the means for clamping the cloth, and for cutting the same.

Figs. 5 and 6 are elevations of the cutter.

Fig. 7 is an elevation of the slide adjustable upon the cloth wrapping plate.

Fig. 8 is a plan view of the said slide.

Fig. 9 is a plan view of the socket member for receiving the free end of said plate.

Fig. 10 is an elevation of said socket member.

Fig. 11 is a section on the line 11-11 of Fig. 8.

Fig. 12 is an enlarged section on the line 12-12 of Fig. 4.

The appliance embodies a suitable frame having the sides 1 which are spaced apart a distance greater than the length of the bolts of cloth. Mounted for rotation between the sides 1 of the frame is a transverse feed roller 2, above which is disposed a parallel pressure roller 3 adapted to hold the cloth C firmly upon the roller 2, to prevent the cloth and roller 2 slipping relative to one another. The roller 3 is carried by a frame 4 pivotally connected by arms 5 pivoted to the sides 1 of the frame, whereby said frame 4 can be swung upwardly out of the way, as indicated in dotted lines in Fig. 2, when the cloth is being applied over the roller 2.

There is provided within the frame a concave receptacle composed of transverse rollers 6 terminally journaled to the sides 1 of the frame, and said rollers are so arranged as to provide a transverse receptacle in rear of the roller 2, said roller being disposed above one side of the receptacle. The bolt B of cloth is dropped within this receptacle and can rotate easily, the rotation of the rollers facilitating this action, and permitting the bolt to move easily within the receptacle.

As a means for holding the bolt B properly within the receptacle, to prevent the bolt shifting longitudinally of itself out of proper position, a plate 7 is disposed within the receptacle between and parallel with the sides 1 of the frame, and is adapted to be adjusted longitudinally of the receptacle to accommodate various lengths of bolts. The plate 7 is provided with a downwardly projecting pin 8 adapted to be inserted downwardly in apertures 9 of a transverse bar 10 secured within the frame parallel with or longitudinally of the receptacle and below said receptacle. The plate 7 can thus be adjusted and held in place in its various adjusted positions.

The rotation of the feed roller 2 is utilized for automatically measuring the cloth as it

is unwound from the bolt, and to this end a small pinion 11 is attached to one end of the roller 2 or its shaft, and meshes with a gear wheel 12 having a pointer 13 attached thereto, said pointer coöperating with a graduated dial 14, upon which is indicated by the pointer the length of material passed over the roller 2. This provides a convenient and accurate means of measuring the cloth.

10 A ratchet wheel 15, as seen in Fig. 3, is attached to the other end of the roller 2 or its shaft, and a pawl or dog 15' carried by the respective side 1 of the frame coöperates 15 with the ratchet wheel 15, to prevent the retrograde rotation of the roller 2. A second pawl or dog 16 also coöperates with the ratchet wheel 15, and is carried by one end of a transverse shaft 17 journaled through 20 the sides of the frame below the roller 2. The other end of the shaft 17 is provided with a handle 18, whereby said rock shaft 17 can be readily manipulated from the operating side of the machine to move the pawl 25 16 into or out of engagement with the ratchet wheel 15. When the pawl 16 is engaged to the ratchet wheel 15, this prevents the further feeding of the cloth.

20 A transverse strip 19 is secured upon the 30 sides of the frame adjacent the rollers 2-3 so that the cloth passes from the rollers over said strip, and said strip has an elongated slot 20 arranged longitudinally thereof to accommodate the cloth cutter. This cloth 35 cutter embodies a handle 21 working within and projecting upwardly from the slot 20, pairs of wheels or rollers 22 and 23 being pivoted to the opposite sides of the handle 21 and contacting with the upper 40 and lower surfaces of the strip, respectively, to guide the cutter for easy movement back and forth along the strip 19. The handle 21 carries a cutter blade 24. The cutting edge of the blade 24 is inclined when the handle 45 21 is in operative position, as seen in Fig. 5.

50 Coöperating with the strip 19 is a clamping or pressing arm 25 composed of two side pieces 26 constructed of sheet metal or other suitable material, and fulcrumed, as at 55 27, to that side of the frame remote from the operating side of the machine. The fulcrum 27 is below one end of the strip 19, and from the fulcrum 27, the side pieces 26 of the member 25 extend upwardly to the strip 19 and then extend along the strip, projecting toward the opposite side of the frame. The 60 pieces 26 are connected by stays 28, adjacent the fulcrum 27, for strengthening the arm or member 25, and the upper edges of the pieces or sections 26 are provided with longitudinal inturned flanges or lips 29 adapted to seat upon the strip 19 adjacent the edges thereof. The flanges or lips 29 do not extend the full length of the strip 65 19, since this is not necessary. Said flanges

are spaced apart sufficiently to permit the wheels 22 of the cloth cutter to move therebetween. The lower terminal of the clamping arm 25 has pivotally connected thereto one end of a transverse rod or link 30, and the other end of said rod is pivoted upon a circular plate or lever 31 mounted for rotation upon an outstanding shelf 32 attached to the side 1 of the frame which is at the operating side of the machine. The plate 31 75 has an outstanding arm or handle 33 whereby it can be conveniently oscillated. When the plate 31 is moved to one position, the rod 30 is pushed toward the opposite side, thereby swinging the arm 25 so that the flanges 80 29 seat upon the strip 19, and when the plate 31 is moved in the opposite direction, the rod 30 is pulled to swing the arm 25 upwardly to the dotted line position as seen in Fig. 4. This will move the arm upwardly 85 out of the way, so that the cloth can pass over the strip 19 without interference, the cutter being moved to one end of the strip 19 out of the way also.

90 The cloth C is wound upon an elongated plate 34, for the purpose of folding the cloth, and said plate 34 is mounted for rotation upon a spindle or shaft 35 disposed longitudinally of the plate 34 between the edges thereof. One end of the spindle 35 is secured to a block or member 36 hinged to that side of the frame remote from the operating side of the machine, whereby the spindle 35 can be swung from a transverse position, as seen in full lines in Fig. 1, in a horizontal plane away from the frame, as indicated in dotted lines in said figure. The free end of the plate 34 is supported by an elongated socket member 37 carried for rotation by that side of the frame at the operating side of the machine, a hand crank 38 being attached to the socket member 37 for rotating it. One end of the socket member 37 is open to receive the free end of the plate 34 when it is swung into operating position, and when the socket member 37 is properly disposed, the plate 34 can be swung out of the same to the dotted line position in Fig. 1.

100 Mounted for sliding adjustment upon the plate 34 is an elongated slide 39, which has pivoted thereto a cam 40 which can be swung against the plate 34 to hold the slide in various adjusted positions, so as to accommodate different widths of cloth. The 105 socket member 37 and slide 39 are each equipped with a spring catch 41 for gripping the end of the cloth, when the end of the cloth is applied to the plate 34, and whereby the cloth will be wound upon said 110 plate 34 when it is rotated.

115 In using the machine, the bolt B of cloth from which a length of cloth is to be taken, is deposited in the receptacle upon the rollers 6, and the cloth is then passed over the 120 125 130

roller 2, the roller 3 being raised out of the way until the cloth is passed over the roller 2. The cloth is then passed over the strip 19 and is attached to the plate 34 by means 5 of the catches 41. Then, with the arm 25 swung upwardly out of the way, and the cutter at one end of the strip 19, the crank 38 is rotated for winding the cloth upon the plate 34, the length of cloth thereon 10 being indicated by the pointer 13 upon the stile 14. After the desired length of cloth has moved past the strip 19, the handle 18 is swung to bring the pawl 16 into engagement with the ratchet wheel 15, said pawl 15 15 being normally moved away from the ratchet wheel 15, and this prevents the movement of the cloth in either direction relative to the feed rolls. The handle 33 is now moved to swing the arm 25 downwardly, so that its flanges 29 press or clamp 20 the cloth tightly upon the strip 19, and then the cutter, which is at that end of the strip 19 adjacent the arm 25, is moved by the hand along the strip 19, and in being so moved 25 will cut the cloth quickly and effectively. The flanges 29 in holding the cloth upon the strip 19 at the opposite sides of the slot 20 will prevent the cloth from slipping as the cutter is moved along the arm 25 and 30 away from the same toward the opposite side of the machine. The plate 34 is then given an additional turn, after the cloth is cut, to complete the winding of the cloth. The cloth which is mounted or folded upon 35 the plate 34 can then be readily removed for purpose of wrapping, since when the socket member 37 is brought to the position illustrated in Figs. 1 and 3, the plate 34 can be swung outwardly, and after the cloth is 40 disengaged from the catches 41, the cloth can be readily slipped off of the plate 34 by an endwise movement. The cloth is thus folded, in order that it can be wrapped conveniently. The present machine facilitates 45 the measuring, cutting and folding of the cloth, and is far superior to the ordinary method of handling the cloth by hand, which involves considerable time, and trou-

ble, as well as producing waste when the cloth is not cut accurately by hand. 50

Having thus described the invention, what is claimed as new is:

1. A device of the character described embodying a frame having cloth holding means, a winding member having one end hingedly connected to the frame, a rotatable socket member carried by the frame for receiving the free end of said winding member, a slide adjustable upon the winding member, and catches carried by said socket member and slide for attaching the end of the cloth to the winding member. 55

2. A device of the character described embodying a frame having cloth holding means, a block hinged to the frame, a spindle carried by said block, a plate rotatable upon said spindle for winding the cloth thereon, a rotatable elongated socket member carried by the frame and having one end open to receive the free end of said 60 plate, a slide adjustable upon said plate, and cloth engaging catches carried by said socket member and slide. 65

3. A device of the character described embodying a frame having cloth holding 75 means and a transverse strip over which the cloth passes while being measured, an arm fulcrumed to one side of the frame below said strip and having side pieces extending along the edges of said strip, said side pieces 80 having flanges adapted to clamp the cloth upon the strip, the arm projecting from said side of the frame toward the opposite side, a cutter movable along the strip between said flanges, operating means carried 85 by that side of the frame opposite the first mentioned side, and a connection between said operating means and arm. 90

As witness that I claim the foregoing as my own, I have hereto affixed my signature in the presence of two witnesses.

JOHN THOMAS TULLIS.
